UNITED STATES PATENT OFFICE.

ARTHUR T. ANDERSON, OF ST. LOUIS, MISSOURI.

FLOOR WAXING AND POLISHING MACHINE.

Application filed December 15, 1923. Serial No. 630,971.

To all whom it may concern:

Be it known that I, ARTHUR T. ANDERSON, a citizen of the United States, and resident of the city of St. Louis and State of Missouri, have invented certain new and useful Improvements in Floor Waxing and Polishing Machines, of which the following is a specification containing a full, clear, and exact description, reference being had to the accompanying drawings, forming a part thereof.

My invention relates to improvements in floor waxing and polishing machines and has for its primary object a machine in which the waxing and polishing members are power driven so that a maximum amount of waxing and polishing can be done with a minimum amount of physical labor.

A further object is to construct a waxing and polishing machine for floors which is so constructed that both operations can be performed with one machine at the will of the operator, the machine being so arranged as to be power driven in either direction.

A still further object is to construct a waxing and polishing machine for floors in which the mechanism is located within a housing, the housing being so arranged as to permit accessibility to all the working parts without the necessity of turning the machine over.

In the drawings:

Fig. 1 is a front elevation of my device viewing the same from the polishing end;

Fig. 2 is a top plan view with part of the casing removed;

Fig. 3 is a longitudinal section showing the device in position for polishing the floor;

Fig. 4 is a similar view showing the machine in waxing position;

Fig. 5 is an enlarged fragmental section of the polishing brush and lower portion of the wax magazine; and

Fig. 6 is a perspective view of one of the spiders employed.

In carrying out my invention, I employ a housing which is composed of members 7 and 8, these members are hingedly secured together at a point indicated by the numeral 9. This point being preferably at the lower rear end of the member 7. The members are held together in closed position by means of a spring catch 10 which is carried by the member 7 and which passes over a tooth 11 carried by the member 8. The member 7 is provided with sides 12 and 13 through which

extends a shaft 14. Secured to the shaft 14 are traction wheels 15 which are provided with pulleys 16. Secured to the member 7 is an electric motor 17 which is provided with a shaft 18. The shaft 18 has its free end secured in bearings 19 carried by the sides 12 and 13. Mounted on the shaft 18 are pulleys 20, 21, 22 and 23. Over the pulley 21 is placed a belt 24, which belt passes around the pulley carried by one of the wheels 15. Over the pulley 22 is placed a belt 25 which passes around the pulley formed integral with the other wheel 15. The belt 25 is a cross belt so that reversed movement can be imparted to the traction wheels 15.

Pivottally mounted on the shaft 14 are spiders 26, to one arm of these spiders is attached the waxing brush 27, the other arm of the spider 26 carries a buffer or polisher 28 and a polishing brush 29. The waxing brush 27 is provided with a pulley 30 around which a belt 31 passes. This belt also passes around the pulley 20. The polishing brush 29 is provided with a pulley 32 and the buffer with a pulley 33, around these two pulleys is placed a belt 34 which also passes around the pulley 23. Formed integral with the spiders 26 are arms 35 which carry pulleys 36 and 37. These pulleys 36 and 37 act as belt tighteners for the belts 24 and 25 respectively. The manner of their operation will be explained in detail later.

Secured to the side 13 is an idler pulley 38 which acts as a belt tightener for the belt 31 when the waxing brush is brought into action. Secured to the side 12 is an idler pulley 39 which is for the purpose of tightening the belt 34 when the polishing operation is in progress. Secured to the spiders 26 is a magazine 39^a in which the polishing compound is located. This magazine is secured by means of braces 40 and 41, and is provided with a hinged lid 42. This lid is maintained in closed position by means of a spring catch 43. It will be noted from Fig. 5 that the lower end of the magazine is open so that the waxing brush 27 forms a closure therefor so that a constant supply of wax is delivered to the waxing brush.

Secured to the spiders 26 and located between the polishing brush and buffer is a tie-rod 44 to which is secured a socket 45. Secured in this socket is a ball which is formed integral with the rod 46. The rod

46 extends through the top of the member 7 and is provided on its upper end with a knob 47. The rod 46 is also provided with a double toothed member 48 which is 5 adapted to engage with either the under or upper side of the top of the member 7. This is for the purpose of placing the various parts of the device in operation, as will be fully described later. It will be noted from 10 Figs. 1 and 4 that the rod 46 extends through a slot 49 and in order to hold the toothed member 48 in proper engagement, a coil spring 50 is employed.

Pivottally secured to the shaft 14 is a yoke 15 51 which is provided with a socket 52 so that a handle 53 can be inserted for guiding the machine.

The device is also preferably provided at each of its corners with rollers 54, these 20 rollers however are only for the purpose of preventing the casing from tilting and scratching the floor.

The member 7 is also provided with a suitable socket 55 so that an electric conductor can be inserted for supplying current to the motor.

The operation of my device is as follows:—

The latch 10 is first lifted and the member 8 swung backward so as to open the housing, the lid 42 is then opened and the waxing and polishing material placed in the magazine 39^a, the housing is then closed and the proper electrical connection made and 35 the motor started. During this operation the double toothed member 48 is so arranged that a portion of it will extend above and a portion below the top of the member 7. The rod 46 being held in this position by means 40 of the spring 50. In this position all belts are sufficiently loose so as not to operate when the motor is started. The next step is to grasp the knob 47, move the rod forward and pull upward thereon, this raises 45 the polishing end of the spider and brings the waxing brush 27 in contact with the floor. This movement also swings back the idler pulley 37, tightening the belt 25 and causing the machine to move rearward as indicated by the arrow in Fig. 4. This movement of the waxing brush also brings the idler pulley 38 into action causing it to tighten the belt 31 and revolve the polishing brush.

55 After the floor has been sufficiently waxed the operation of the machine is stopped by again placing the toothed member 48 in neutral position. The handle and yoke are then reversed into the position shown in 60 Fig 3 and the knob 47 depressed so as to bring the polishing brush and buffer in contact with the floor. This operation moves with it the pulley 36 which tightens the belt 24 and causes the device to move in the direction of the arrow in Fig. 3. This same

movement also causes the idler pulley 39 to tighten the belt 34 and thus places the polishing end in operation, while at the same time the waxing brush ceases to revolve and consequently no more wax is delivered to the 70 floor.

I may if desired eliminate the power drive from the wheels 15, in the event this is found desirable as it most probably will be with some machines for domestic use, and I therefore do not desire to limit myself to the precise construction of machine as illustrated in the drawings, because a small sized machine can be readily propelled by 75 manual power. But in either event the waxing and polishing members are power driven so that floor waxing can be accomplished with a saving of time and manual labor.

Having fully described my invention, what I claim is:—

1. In a floor waxing and polishing machine comprising a housing, a spider pivotally mounted therein, a waxing means carried by one portion of said spider, a polishing means carried by the other portion of said spider, means carried by said spider for rocking the same whereby either said waxing means or said polishing means may be brought into contact with a floor, and means for placing said means in rotation simultaneously with its contact with the floor.

2. A floor waxing and polishing machine comprising a housing, a spider pivotally mounted therein, a waxing element carried by one portion of said spider, a polishing element carried by another portion of said spider, means for rocking said spider whereby one of said elements may be brought into contact with floor and the other element simultaneously raised therefrom, means for placing the contacting element in rotation and means for holding said element in such contact.

3. A floor waxing and polishing machine comprising a housing composed of two sections, a shaft having wheels located in one of said sections, spiders mounted on said shaft, a waxing brush carried by one portion of said spider, a polishing brush and a buffer carried by one portion of said spider, a motor located in the housing, driving means connected to said motor and to said waxing brush, a second driving means connected to said motor and to the polishing brush and buffer, means for bringing said polishing brush and buffer or said waxing brush into contact with the floor to be waxed and polished, said means simultaneously tightening the driving means of the mechanism brought in contact with the floor, whereby the same is placed in operation.

4. A floor waxing and polishing machine comprising a housing composed of two sections, a shaft having wheels located in one

- of said sections, spiders mounted on said shaft, a waxing brush carried by one portion of said spider, a polishing brush and a buffer carried by one portion of said spider,
- 5 a motor located in the housing, driving means connected to said motor and to said waxing brush, a second driving means connected to said motor and to the polishing brush and buffer, means for bringing said
- 10 polishing brush and buffer or said waxing brush in contact with the floor to be waxed and polished, said means simultaneously tightening the driving means of the mecha-
- nism brought into contact with the floor, whereby the same is placed in operation, 15 and a magazine located above and communicating with the waxing brush.
5. The floor waxing and polishing machine of claim 4 in which the wheels carried by the shaft are adapted to be power 20 driven and placed in operation simultaneously with the operation of the waxing and polishing means.

In testimony whereof, I have signed my name to this specification.

ARTHUR T. ANDERSON.
